UNITED STATES PATENT OFFICE.

WALBORG AHLMGREN, OF NEW YORK, N. Y., ASSIGNOR OF ONE-THIRD TO HENRY C. KARLSON, OF HASBROUCK HEIGHTS, NEW JERSEY, AND ONE-THIRD TO CHARLES A. BURSELL, OF NEW YORK, N. Y.

TOY CAROUSEL.

1,389,926.

Specification of Letters Patent.

Patented Sept. 6, 1921.

Application filed July 31, 1920. Serial No. 400,471.

To all whom it may concern:

Be it known that I, WALBORG AHLMGREN, a resident of the borough of Manhattan, in the county, city, and State of New York, 5 have invented certain new and useful Improvements in Toy Carousels, of which the following is a specification.

This invention relates to a roundabout for dolls and it appertains more especially to 10 such merry-go-round devices which are operated by hand power.

One of the objects of the invention is to provide a device of the character described with improved means for rotating a figure 15 carrying member.

Another object is the production of a device of the nature set forth including means enabling one or more operators to impart rotation to said member.

20 A further object is the provision in a device of the kind referred to of traveling and relatively stationary elements positively oscillated upon motion of the rotary member.

Still another object is to produce a device 25 of the type specified wherein dolls or other toys may be secured to the lower part of the said rotatable member.

A general object is to supply a device of 30 the species mentioned which shall be simple and strong; conveniently assembled or taken apart for packing in a small space; easily and safely operated without liability of getting out of order; besides, being amenable to low cost of manufacture.

35 Other objects of the invention will in part be obvious, and also be brought out more fully in the detailed description hereinafter contained.

The invention consists in the novel features 40 of construction, parts, combinations and sub-combinations of elements herein specified with reference to the accompanying drawings, and recited in the claims herewith appended.

45 In the said drawings:—

Figure I is an elevational view of this improved doll carousel, parts being broken away and others omitted;

Fig. II is a broken top plan view of the 50 device illustrated by the preceding view, the lower parts being omitted; and

Fig. III is a sectional plan taken on the line III-III of Fig. I looking down in the

direction indicated by the arrows pertaining thereto, parts being omitted.

55 Referring specifically to the various views of the drawings, the reference numerals "11-12" and "13-14" denote respectively, longitudinal and transverse arms mortised one into the other at their middle parts to 60 constitute a cruciform base A. Into openings provided at the intersection of these arms and also at or near the extremities of the longer longitudinal arms 11-12, are stepped endwise shouldered uprights 17, 18 65 and 19. The last named, 19, may be shorter than the two others, 17, 18, which are of the same height and united by a brace 20 spanning their upper ends. This brace and the base A with a central and outboard uprights 70 thereon constitute the stationary members of the structure.

Around the said central member 17, intermediate of the base and brace aforesaid, is rotatably arranged a member B, composed of 75 top and bottom carriers C and D, maintained at the proper distance apart, as by means of spacer rods or posts 23, having their extremities shouldered to fit into openings provided therefor at the outer portions of the 80 said carriers. As shown, the lower carrier D is made on the order of a disk 24, which has formed near the periphery thereof in offset relation to the upstanding post elements 23, a number of cutouts or openings 85 25, the purpose whereof will be more fully hereinafter referred to. The upper carrier C is preferably constructed like a four-armed spider having branches 26-27 and 28-29 mortised together at their central portions. 90 Nevertheless, no limitation is intended in this respect, as either or both of the upper and lower carriers could embody disks or spiders in their structural makeup. The centers of the latter are suitably bored so as 95 to readily revolve around the stationary central upright 17.

In proximity to the top and bottom faces of the said upper and lower carriers are connected thereto, as by pins or dowels 31, one 100 or more spools 32 and 33 of which the bottom one may be provided with a plurality of cord receiving grooves such as 34 that may be separated by intervening ridges or flanges 35. Winding one, to the left for instance in the topmost single grooved spool,

32, the other right hand, which may be on the upper one of the lower or plural spools, and secured endwise therein, are branches 38, 39 of an operating cord 40. The said branches of the cord are led through guide openings 41, 42 provided in the taller outboard upright 18, substantially opposite to the central portions of the grooves. The arrangement is preferably such that when 10 most of the cord is wound up on one spool, for instance on 32 as shown, the other groove 34, is almost bare. It will be understood, that if a pull be given to the said cord 40, adjacent to its upper guide 41, the tangential strain of the cord branch 38, upon the spool 32 will tend to impart to the upper carrier of the rotatable member B a turning motion which can be continued until all 15 or nearly all of the cord has been unwound 20 from the said spool 32. At the same time as this occurred, the outer cord branch 39 kept winding around the upper one of the lower spools 33, by reason of the fact that it was originally wound upon the latter in 25 the opposite direction. Now, if the operator commences to exert an outward pulling action upon the cord where it passes the lower guide opening 42, the rotatable member will again be revolved, but contrary to 30 its first rotary movement, and the cord's upper branch 38 will be re-wound ready for another operation. As indicated particularly in Fig. I, the shorter outboard upright 19 is likewise provided with apertures 45, 46, which, however, are spaced closer together and constitute guides for 35 another operating cord 47. The latter has branches 48, 49 wound oppositely around the middle and lowermost grooves 34 of the bottom spool 33 and fill a function corresponding to that of the beforementioned 40 cord 40. Thus it will be seen that two operators can by alternately or simultaneously pulling on the said cords 40 and 47, keep the rotatable member spinning around, first in 45 one direction and then in the other. While it appears that the member B is furnished with one single spool above and three spools below the same, it is conceivable that two such spools could be placed at the top and 50 bottom of their respective carriers. Furthermore, it is possible to locate all of the spools beneath the lower carrier, or to combine them in some other manner and still 55 obtain the same result as in the structure illustrated.

Sustained from the arms of the upper carrier C, or by some other part of the rotatable member so as to travel therewith, 60 is an oscillatable element E, which may be in the nature of a swing composed of pendants 52 joined at their lower ends by a cross-piece 53. This swing as shown is 65 flexibly connected, as for example by inter-engaging eye-screws or screw hooks 54, 55

entered into the underside of one of the arms of the top carrier C, as also endwise into the upper extremities of the said pendants 52. A doll or other appropriate figure F is indicated in dot-and-dash lines, as being 70 seated on the cross-piece 53, and held in position thereon, as by a string or band 56. The latter is passed through suitable apertures 57 in the pendants 52 and thence around the doll after which its ends are tied 75 together.

The means for imparting oscillatory motion to aswing when the member B is rotated can be varied. By preference, it may consist of a dowel or other projection 60 80 applied in any suitable manner to the stationary part of the structure, as for instance by inserting it into a hole bored therefor in the central upright 17. The free terminal of this dowel extends into the 85 path of the inner end of the cross-piece 53 and serves to delay the latter, acting as an obstruction against which the swing hits when partaking of the travel of the revolvable member B. Although only one swing 90 has been shown, it stands to reason that a pair or all of the arms of the upper carrier C could be equipped therewith if so desired.

Another but normally fixed swing G of 95 similar construction as that before described in conjunction with the rotatable member, is represented on the drawings as supported in offset relation to one of the stationary members, which may be the central upright 100 17. As shown, an arm 61 received by its inner extremity in a suitable seat or opening pertaining to the said upright, reaches out therefrom a certain distance below the cross-piece 53, of the swing E, so as to clear the 105 lower part of the doll seated thereon. The swing G is attached to the said arm 60 in a flexible or jointed manner similar to that of the before described swing E, in order to have a like articulated connection insuring 110 for it a positive oscillating movement. This may be obtained through the instrumentality of a dog or obstruction 62, which in the present instance is traveling with the 115 rotatable member, being as indicated, lodged in a recess provided therefor in one of the posts 23. The said obstruction 62, as will be noted, has its free terminus disposed in a path intersecting the adjacent end of a cross-piece 53^a pertaining to the swing G. 120 From this arrangement it follows that when the member B is revolved, recurrent impacts are given to the element G which will set it a-swinging. There may be provided in the upright 17 several openings as 63, so as 125 to admit of the employment of more than one arm with the thereto connected swing. It will be perceived that the movable and stationary elements E and G are located in vertically spaced or tiered relation to each 130

other and to the lower carrier D, in order that any interference between the articles respectively carried by them shall be avoided.

The amount of oscillation of the normally fixed swing G can be varied by allowing the post 23 a slight turning movement upon its own axis, in the carriers C and D, so that the obstruction 62 may be thrown more or less into the path of the cross-piece 53^a as suggested at right of Fig. III.

At 66, 67 are indicated openings or recesses capable of receiving the shanks of the arm 61 and the dog 62 respectively, thus also enabling the lower swing G to be carried by and to travel in unison with the rotatable member. In such a case the dog 62 would be held to the upright 17 the same as the upper obstruction 60, so as to function in a like manner. The result of this construction is that the said member B may optionally be made to include one or more sets of swings disposed at different elevations. Moreover, the outboard upright 18 can be provided with a seat 68, which simply may be a hole running slantwise in the same. This seat is adapted to receive the shank part of the arm 61, the outer end of which in that case extends obliquely. Then by causing the dog 62 to project in an outward direction instead of inwardly as shown, it will impact against the cross-piece 53^a of the swing G as the member B is revolved. Preferably, the coupling between the flexibly inter-engaging connections 54, 55 is separable, by reason of which either or both of the swing elements E and G may be removed from their respective supports, and will thereby allow the member B to rotatably carry dolls or other objects of larger magnitude than otherwise could be accommodated thereon.

As hereinbefore stated, the lower disk-like carrier D is formed with recesses or openings 25, which may be of circular or of any other shape. These recesses are provided for the purpose of receiving therein the legs or feet of dolls or analogous figures H, and are designed to prevent them from moving about when the member B is turned upon its axis. These dolls are generally placed with their backs against the spacer posts 18 and held thereto by any suitable securing means. The latter may, in similarity to the fastenings 56 pertaining to the swings E and G, consist of bands 70 threaded through apertures 71, in the said posts 18, thence passed around the figures thereto appertaining, and tied together at their ends. In order to prevent the bands from being pulled out of their apertures the former are preferably provided at each terminal of the latter with knots or like enlargements 72.

A toy constructed and arranged in accordance with the foregoing description, can easily be made of wooden strips and dowels,

readily put together or taken apart for shipment, in knock-down condition, and will during its erection and manipulation afford to children of all ages, a source of interest, in an educational sense as well as for amusement purposes, because of its varied forms of motion whereof its constituent elements partake.

It is to be understood that the invention herein disclosed is not limited to the precise details of construction shown and described, nor to any particular structural arrangement by which the same may be carried out in practice, as numerous changes, alterations or modifications, may be effected therein without materially departing from the fundamental principle of the invention or even sacrificing any of its main advantages. The right to make all such changes, alterations, or modifications, is therefore reserved.

Having described my invention what I desire to secure by Letters Patent and claim is:—

1. A device of the character described including a rotatable member, a fixed member extending parallel therewith, positive means for imparting motion to the former, an oscillatable element carried by said member, and abutting means for causing oscillation of said element when the first member is rotated relatively to the second member.

2. A device of the character described including a revoluble member, an instrumentality for actuating the latter, oscillatable elements spaced in vertically offset relation to said member, one element being arranged to travel past the other, and means adapted to impart intermittent oscillatory motion to said elements as the member is revolved.

3. A device of the character described including a fixed member, another member rotatable therearound, mechanism for imparting rotation to said second member, an oscillatable element sustained from the latter, another oscillatable element supported from said fixed member, said elements being arranged to pass each other, and means carried by each member for causing oscillation of the element of the opposite member upon rotation of the second member.

4. A device of the character described including a revoluble member, another member centrally fixed with relation to the former, means for imparting motion to the member first named, a swing carried by said fixed member, and a laterally projecting obstruction on said revoluble member adapted to strike said swing when passing the same and thereby cause it to oscillate.

5. A device of the character described including a fixed member, another member rotatable relatively thereto, mechanical means for imparting positive rotation to said other member, a swing traveling with the rotary member, and an obstruction intermediate of

- said fixed member and said swing against which the latter is adapted to strike during its travel whereby oscillation is imparted thereto.
- 5 6. A device of the character described including a member having a carrier, a fixed member around which the former is revoluble, supporting means extending from said fixed member, swings suspended from said carrier and said means, obstructions projecting from both members adapted to be struck by and to strike said swings to cause them to oscillate, and an instrumentality for revolving the first named member.
- 10 7. A device of the character described including a fixed upright, a member rotatable therearound composed of carriers with spacers therebetween, means for rotating said member, an arm extending out from said upright, swings flexibly connected to the upper one of said carriers and to said arm, and dogs carried by the upright and one of said spacers in the path of said swings adapted to impart oscillatory motion thereto upon rotation of the member.
- 15 8. A device of the character described including a revoluble member, a supporting element rising therefrom, said member having a cutout portion offset inwardly from said element, means for holding the upper part of a doll to the element while the lower part thereof is received in said portion, and an instrumentality for revolvably actuating the member.
- 20 9. A device of the character described including a base, an upright fixed thereon, a member rotatable about said upright, a spool also revoluble around the same interposed between said base and said member being connected to the latter, and band-like means having branches secured endwise to said spool, said means being continuous and
- 25 both branches thereof passing between the base and the member, one branch winding left and the other right-hand, in such a manner that pulling on said branches alternately will impart rotation to the member in opposite directions.
- 30 10. A device of the character described including a base, a fixed member extending up therefrom, another member composed of spaced apart carriers revoluble around said fixed member, spools loosely mounted on the latter in operative connection with said carriers, and a cord reaching to said spools having branches wound therearound in opposite directions, whereby alternate pulling on the latter will revolve said second member first one way and then the other.
- 35 11. A device of the character described including a base, fixed uprights thereon, a brace between the upper ends of said uprights; a member composed of spaced carriers rotatable around one of the uprights; spools interposed between said brace, said base and the upper and lower carriers respectively connected up with the latter; and a cord having branches guided in the other one of the uprights winding separately right and left-hand on said spools, so that pulling alternately on said branches will impart rotation to said member in opposite directions.
- 40 12. A device of the character described including a base, a substantially central upright fixed thereon, another stationary upright on said base offset from the one first named and provided with a guide, a carrier rotatable about said central upright, a spool revolvably supporting said carrier over the base, and a carrier-operating cord passed through said guide and having branches wound right and left around said spool.

WALBORG AHLMGREN.
